TARGET APPARATUS

Rudolf D. Delamere, Victor G. Williams, Edward R. Grange, and Hugh Heaton, Toronto, Ontario, Canada

Application September 22, 1941, Serial No. 411,854

13 Claims. (Cl. 273—105.2)

This invention relates to target apparatus and more particularly to miniature moving targets of a type suitable for use with the practice gun disclosed in our co-pending application Serial No. 402,540, filed July 15, 1941, and our object is to provide simple target apparatus for reproducing on a small scale the movable object which it is desired to practice hitting. Other objects we have in mind will hereinafter appear.

The invention is hereinafter more fully described and is illustrated by way of example in the accompanying drawings in which

Fig. 1 is a front elevation of the apparatus;

Fig. 2 a side elevation thereof;

Fig. 3 a rear elevation, on an enlarged scale, of the central part of the apparatus;

Fig. 4 a cross-section on the line 4—4 in Fig. 3;

Fig. 5 a sectional detail, partly broken away, of the outer and inner arms;

Fig. 6 a diagrammatic view showing the cam and various positions of the arms and target thereon;

Fig. 7 a side elevation on an enlarged scale, of the central part of the apparatus showing the means for driving the sound apparatus;

Fig. 8 a diagrammatic view of the sound apparatus; and

Fig. 9 a detail of the housing.

In the drawings, like numerals of reference indicate the corresponding parts in the different views.

The apparatus comprises one or more targets 1 carried on rotatable arms, each consisting of an inner and an outer part or arm 2, 3. As the arms rotate, the outer parts 3 are moved relative to the inner parts 2 to cause the targets 1 which are miniature aeroplanes, to dive in a substantially straight line during a portion of each revolution. The targets are also moved relative to the outer parts to simulate the attitude of an aeroplane while diving and coming out of a dive. The size and speed of the targets 1 will be any predetermined fraction (preferably one-fiftieth) of the size and speed of the target it is desired to practise hitting and to correspond substantially to the reduced muzzle velocity of the type of gun which it is desired to practise shooting.

The whole apparatus is mounted on a base 4 which will be suitably supported above the ground or the floor of a building so that the diving targets may be set at any desired distance above the eyes of the operator to correspond to the usual distance actual diving planes clear the ground. On the base 4 is mounted a speed reducer of any well known type having a casing

5, a low speed shaft 6 journaled in a hub 7, and a high speed shaft 8. On the hub is adjustably secured a stationary cam 9 which is locked in its adjusted position as hereinafter described.

5 A drum 10 secured to the low speed shaft 6 includes a hub keyed to said shaft, a disk secured to the hub, a peripheral wall secured to the disk; and an inwardly directed flange secured to said wall for encasing the front side and periphery 10 of the cam 9. To the peripheral wall of the drum are secured two tubular inner arms 2 which are spaced diametrically opposite one another and extend outwardly from the drum. To the outer end of each arm 2 is secured a casing 11. In each casing a lever 12 is pivoted at 13 and to each lever is secured a tubular outer arm 3. A housing 14 is carried at the outer end of each outer arm 3 and the targets 1 are secured to spindles 15 journaled in the housings 14. Since the arms 2, 3, casings 11, levers 12, and housings 14 are identical, only one set of these parts will be described.

To one end of a push rod 16 is secured a clevis 17 which carries a journal on which an anti-friction roller 18 is journaled. The journal is pivotally mounted in the free end of a forked link 19 which is pivoted inside the drum 10 so that the roller 18 bears against the cam face of the cam 9. Each inner arm 2 has one of such push rods 16 passed therethrough, the end of each push rod remote from the roller being pivotally connected with the adjacent lever 12. Springs 20 disposed on the rods 16 bear against seats secured within the arms 2 and against the ends of the clevises 17, or collars engaging the latter, for maintaining contact between the rollers 18 and the cam 9.

In each of the outer arms 3 is axially movable a trip rod 21 which is provided with a lateral projection 22 pivoted at 23 in the casing 11. The other end of the trip rod slides in a bearing in the housing 14 and has a catch 24 threaded therein. A finger 25 secured to the target spindle 15 has a spring 26 which urges the finger into engagement with an adjustable stop 27 in the housing to maintain the target in its normal position. A pawl 28 adapted to be engaged by the catch 24 is pivoted on the free end of the finger 25 and is provided with a spring 29 tending to maintain the pawl in engagement with an adjustable stop 30 on the finger. Preferably two targets 1 are secured to each spindle 15, the outer ends of the spindle may be flattened to lie flat against the adjacent inner ends of the aeroplane targets. As the spindle is rocked on its axis, the

targets are rocked longitudinally of the fuselages thereof to vary the angle of incidence.

The cam 9 is so shaped that, as the drum 10 and arms 2, 3 revolve around it, the push rods 16 will be axially moved to rock the levers 12 and cause the outer arms 3 to be swung towards and away from the inner arms 2. Thus the angle between the outer and inner arm of each set of arms is greater at the point A in the dotted path of the targets than at the point B therein. In other words a portion of the cam is shaped to cause the outer arm to swing towards the inner arm whereupon the targets carried by said outer arm will travel in a substantially straight line to simulate a bomber making a dive. During this relative movement of the outer and inner arms, the outer arm and its lever 12 are rocked relative to the pivot 23 of the trip rod whereby the catch 24 and the outer arm 3 are moved towards one another. The catch engages the pawl 28 on said movement and rocks the finger 25 to cause the spindle 15 and targets 1 to be rocked so that the longitudinal axes of the fuselages will follow the paths of flight of the targets. The engagement of the catch 24 and pawl 28 is such that when the targets reach the end of the dive, indicated at B, the pawl swings out of the path of the catch whereupon the finger 25 and targets 1 are returned by the spring 26 to their normal positions. Thus the angle of incidence of the targets is changed, as in an actual aeroplane when coming out of a dive. As the targets move towards the point A, to begin a new dive, the outer arm is moved away from the inner arm whereby the catch 24 and the outer arm 3 are moved away from one another. The catch is adapted to move past the pivoted pawl 28 by rocking it on its pivot against the tension of its spring 29.

To prevent missiles shot at the rear target from entering the drum 10, we provide a stationary disk or shield 31 which is cut away to fit on the speed reducer casing 5 and which may be secured thereto. The cam 9 is provided with a block 32 which extends laterally to the disk 31 and has a handle 33 secured thereto by means of bolts. The handle is at the outer side of the disk and the bolts pass through an arcuate slot 34 in the disk. A locking stud 35 also passes through the slot 34 and is threaded in the block 32 whereby the cam may be locked to the disk in any desired position, within the range of the slot, to regulate the angle of the diving targets relative to the ground.

On the base 4 is slidably mounted a motor 36 which, by means of a pulley 37, a belt and a pulley on the high speed shaft 8 of the speed reducer drives the latter. The pulley 37 may be of the split V type adapted by adjusting the tension of the belt, also V shaped in cross-section, to vary the position thereof in the V of the pulley. Thus the speed of the shaft 8 and of the targets may be finely regulated. The motor is movable by a crank to adjust the tension of the belt drive between the motor and said shaft. The high speed shaft 8 may carry a flywheel and drive, by gearing 38, the usual gears of the speed reducer. The gearing 38 may also drive a ratchet or other type of over-running shaft 39 which may drive, or be, the usual sprocket shaft of ordinary sound producing apparatus 40 which includes an endless film 41 having a sound track thereon, an amplifier and a loud speaker. The sound produced is an imitation of that produced by an aeroplane as it begins to dive, dives, and comes

out of the dive. The ratchet shaft 39 may be manually turned in a forward direction of rotation relative to the gearing 38 to synchronize the sound producing apparatus with the targets.

5 The outer ends of the inner arms 2 may be supported from the drum 10 by any suitable means such as the truss rods 42.

It will be distinctly understood that various modifications may be made without departing 10 from the spirit of our invention.

What we claim as our invention is:

1. Apparatus of the class described comprising a rotatable inner arm; an outer arm pivotally carried by said inner arm for carrying a target, the pivot of the outer arm being substantially parallel to the axis of rotation of the inner arm; and means for actuating the outer arm to swing relative to the inner arm during the rotation of said arms.

20 2. Apparatus of the class described comprising a rotatable member; an inner arm carried by said member; an outer arm pivotally carried by said inner arm for carrying a target; a push rod axially movable relative to the inner arm; and means including a stationary cam for controlling the 25 movements of the push rod, the latter being connected with the outer arm to cause the said arm to swing relative to the inner arm during the rotation of said arms about the cam.

30 3. Apparatus of the class described comprising a stationary cam; a rotatable drum encasing said cam; a tubular inner arm secured to said drum and communicating with the interior thereof; a casing carried by the end of the inner arm remote from the drum; a lever pivoted in said casing; an outer arm secured to said lever; a push rod axially movable in said inner arm, one end of the rod being pivotally connected with the lever; and means for maintaining the other end 40 of the rod in engagement with the cam to cause the outer arm to swing relative to the inner arm during the rotation of said arms about the cam.

4. Apparatus of the class described comprising a stationary cam; a rotatable drum encasing said cam; a tubular inner arm secured to said drum and communicating with the interior thereof; a casing carried by the end of the inner arm remote from the drum; a lever pivoted in said casing; a tubular outer arm secured to said lever; a housing carried by the end of the outer arm remote from the lever; a target simulating an aeroplane pivotally carried on said housing; a push rod mounted in and axially movable relative to said inner arm; means for ensuring the rod will 55 follow the contour of the cam, the rod being connected with the lever to cause the target to simulate a dive bomber; means for normally positioning the target relative to the housing; and trip mechanism in said outer arm and housing for changing the angle of incidence of the target during its diving movement.

5. Apparatus of the class described comprising a stationary cam; a rotatable drum encasing said cam; a tubular inner arm secured to said drum and communicating with the interior thereof; a casing carried by the end of the inner arm remote from the drum; a lever pivoted in said casing; a tubular outer arm secured to said lever; a housing carried by the end of the outer arm remote from the lever; a target simulating an aeroplane pivotally carried on said housing; a push rod mounted in and axially movable relative to said inner arm; means for ensuring the rod will follow the contour of the cam, the rod being connected with the lever to cause the tar-

get to simulate a dive bomber; means for normally positioning the target relative to the housing; and a trip rod adapted to engage the positioning means, the trip rod being slideable in said outer arm and provided with a lateral projection pivoted in said casing at a point spaced from the pivot of the lever so that, as the outer arm is rocked towards the inner arm, the outer end of the trip rod and the lever are moved towards one another to actuate the positioning means and thereafter release the said positioning means.

6. Apparatus of the class described comprising a stationary cam; a rotatable drum encasing said cam; a tubular inner arm secured to said drum and communicating with the interior thereof; a casing carried by the end of the inner arm remote from the drum; a lever pivoted in said casing; a tubular outer arm secured to said lever; a housing carried by the end of the outer arm remote from the lever; a target simulating an aeroplane pivotally carried on said housing; a push rod mounted in and axially movable relative to said inner arm; means for ensuring the rod will follow the contour of the cam, the rod being connected with the lever to cause the target to simulate a dive bomber; a finger secured to the pivot of the target; an adjustable stop for limiting the movement of the finger in one direction of rotation; a spring urging the finger towards the stop; a pawl on said finger; and a trip rod adapted to engage said pawl, the trip rod being slideable in said outer arm and provided with a lateral projection pivoted in said casing at a point spaced from the pivot of the lever so that, as the outer arm is rocked towards the inner arm, the outer end of the trip rod and the lever are moved towards one another to actuate the finger and thereafter move out of the path of the pawl whereupon the finger re-engages its stop.

7. Apparatus of the class described comprising a stationary cam; a rotatable drum encasing said cam; a tubular inner arm secured to said drum and communicating with the interior thereof; a casing carried by the end of the inner arm remote from the drum; a lever pivoted in said casing; an outer arm secured to said lever; a link having one end pivotally connected with the drum, the other end of said link carrying a pin; an anti-friction roller journaled on said pin for engaging the cam; a push rod axially movable in said inner arm; a clevis pivotally mounted on said pin and secured to one end of said push rod; a spring seat in said inner arm; and a spring disposed on the push rod engaging said seat and the clevis for maintaining contact between the roller and the cam, the other end of said push rod being pivotally connected with the lever.

8. Apparatus of the class described comprising a rotatable member; an inner arm carried by said member; an outer arm pivotally carried by

5 said inner arm for carrying a target; a stationary cam; a link having one end pivoted on the rotatable member; a spring actuated push rod having one end connected with the said outer arm and the other end connected with the free end of the link; and an anti-friction roller carried by the push rod for engaging the cam.

9. Apparatus of the class described comprising speed reducing mechanism having a casing, a high speed shaft and a low speed shaft; a cam carried by said casing; a drum secured to the low speed shaft for encasing one side of the cam and the periphery thereof; target carrying means carried by said drum; a pair of targets mounted side by side on said means; and a stationary disk on said casing to prevent missiles from striking the other side of the cam.

10. Apparatus of the class described comprising speed reducing mechanism having a casing, a high speed shaft and a low speed shaft; a cam adjustably carried on said casing; a drum secured to the low speed shaft for encasing one side of the cam and the periphery thereof; target carrying means carried by said drum; a pair of targets mounted side by side on said means; a stationary disk on said casing to prevent missiles from striking the other side of the cam, the disk having an arcuate slot therein; and means passed through said slot for turning said cam and for releasably locking it as adjusted.

11. Apparatus as claimed in claim 2 in which the stationary cam is adjustable to vary the points at which the outer arm moves relative to the inner arm, and in which means is provided to lock the cam as adjusted.

12. Apparatus as claimed in claim 6 in which a catch for engaging the pawl is carried by the trip rod and is adjustable longitudinally thereof.

13. Apparatus of the class described comprising a rotatable inner arm; an outer arm pivotally carried by said inner arm, the pivot of the outer arm being substantially parallel to the axis of rotation of the inner arm; a target simulating an aeroplane carried by the outer arm so that its longitudinal axis is arranged in the path of flight of the target, the target being pivoted on said outer arm transversely of said longitudinal axis and substantially parallel to the axis of rotation of said inner arm; means for actuating the outer arm to swing relative to the inner arm during the rotation of said arms to cause the target to move in a substantially straight line during a portion of each revolution of said arms; and means controlled by said actuating means for rocking the target longitudinally of said longitudinal axis to cause the latter to follow the path of flight of the target.
